UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 25, 1919. Serial No. 340,542.

To all whom it may concern:

Be it known that I, SAMUEL B. WILLIAMS, Jr., a citizen of the United States, residing at Brooklyn, in the county of Kings, State 5 of New York, have invented certain new and useful Improvements in Telephone-Exchange Systems, of which the following is a full, clear, concise, and exact description.

This invention relates to telephone exchange systems employing machine switching, and more particularly to private branch installations wherein connections may be made between stations within the private branch installation, or between such stations 15 and a central office.

In many business houses where the greater part of the calls are made between substations within the private branch exchange, the number of central office calls is not sufficient to occupy the full time of an operator. 20 It is, however, desirable to have provision made for answering incoming central office calls, for giving information to persons calling within the branch exchange, and for supervising certain outgoing central office calls. 25 To provide such service has in the past required either a switchboard and operator at the branch exchange or else a far greater number of central office trunk circuits than the number of calls between branch exchange stations and central office 30 stations warranted.

It is the object of this invention to provide such service at the branch exchange 35 without either a full time operator or an unnecessarily large number of central office trunk circuits.

According to one feature of the invention one or more substations hereinafter termed 40 receiving stations, having no special equipment, are designated to provide operator service. These substations may be those of certain clerks whose incidental duty it is to answer calls either from the central office 45 or from stations within the branch exchange when information is desired. Inasmuch as it requires only a small portion of the time of one of these clerks and as she need have 50 no special equipment other than an ordinary telephone subset provided with a simple calling device, it is possible without undue

expense to have an intelligent person answer incoming central office calls, which is a great advantage to a business.

According to another feature of the invention 55 a trunk circuit is provided which terminates in four places, namely an operator's position at the central office, a non-numerical switch having access to receiving stations, the bank terminals of branch exchange final selector switches and the brushes of companion final selector switches at the branch exchange.

Still another feature of the invention is the provision of a trunk circuit terminating 60 in only three of the previously named points, all within the branch exchange, namely, a non-numerical switch having access to receiving stations, the bank contacts of final selector switches and the brushes of companion final selector switches. 65

Referring to the drawings, Figs. 1, 2 and 3, with Fig. 2 to the right of Fig. 1 and Fig. 3 above Fig. 2, show diagrammatically the 70 circuits employed in completing connections between various substations within the branch exchange and between such stations and a central office.

Fig. 4 shows partly schematically and partly diagrammatically all the possible 75 types of connections in this system when the number of branch exchange substations is small; and Fig. 5 is a simplified diagram of the connections in a system of this character when the number of branch exchange substations is great enough to require the use 80 of first selector switches in addition to final selector switches.

To the left of the dotted line in Fig. 1, a 85 substation A and a line finder switch 100 with circuits therefor are shown. In the dotted left-hand lower corner of Fig. 1 are shown relays individual to the group of line finders which have access to the substation A. To the right of the dotted line in 90 Fig. 1 and to the left of the dotted line in Fig. 2, is shown a final selector switch 200 with the three types of circuit terminals on which it may be set. To the right of the dotted line in Fig. 2 is a trunk circuit linking 95 the final selector terminals with a non-numerical or hunting switch 25 and a com-

panion final selector switch 20. In Fig. 3 is another trunk circuit similar to the one in Fig. 2, but also leading to multiple jacks at a central office, one of which is indicated 5 within the dotted rectangle.

Figs. 6 and 7 represent a detail of the circuit of Fig. 1 and show the alternate connections of the cut-off relay. Fig. 6 represents the connection when the associated line is a restricted service line and Fig. 7 represents the connection when the service of the associated line is not restricted.

The receiving station F shown in Fig. 3 is provided with a cordless board but it will be apparent from the description hereinafter that it performs no function which may not be done just as well by a station such as E.

20 The structure of the line finder, final selector, and companion final selector switches may be of the type fully disclosed in the patent to Forsberg No. 1,252,420 of January 8, 1918, but it is understood that these 25 switches might be of any well known type.

In Fig. 4 are shown banks of terminals divided into levels 400, 401, 402, 403 and 404 to which substations A, B, C, D and receiving stations E and F are connected. Additional 30 levels of bank terminals, not shown, may be provided in accordance with the number of lines in the exchange. Each heavy dot, 31, 32 represents a set of terminals and each line 405, 406 represents a set 35 of conductors making up a trunk circuit. Line finder switches 100, final selector switches 200, and two kinds of companion final selector switches 20 and 300 are arranged to engage with their brush sets one 40 of the multiple terminal sets of any line in any level. Non-numerical or hunting switches 25 and 30 are arranged to hunt over the level 402 which leads to receiving stations E and F.

45 It will thus be seen that any subscriber may by initiating a call have his line picked up by a line finder 100. By operating his calling device he may set a final selector 200 in its primary movement so that one of its 50 brush sets 407 or 408 will be ready to travel over a group of terminals in any level of the bank. If he has chosen a level 402, 403 or 404 he may then direct the switch 200 in its secondary movement to any line in that 55 level when a call will be complete to the wanted subscriber. If the subscriber sets the final switch 200 in its primary movement on level 400 it will in its secondary movement hunt an idle central office trunk 60 406. If he has chosen level 401, however, the switch 200 will in its secondary movement automatically select an idle trunk 405 and the hunting switch 25 will select an idle receiving station E or F. If the calling 65 subscriber desires the call extended, the re-

ceiving subscriber operates his calling device to set the companion final selector switch 20 on any desired level of terminals. The switch 20 may be set directly on the terminals of any station in the branch exchange, or it may be directed in its primary movement to the central office level 400, when in its secondary movement it will automatically select an idle trunk 406.

70 Provision is made for restricting certain substations to interior calls, so that if a subscriber at one of these stations should set a final selector 200 on level 400, a connection would be completed through auxiliary brush 201 and the commutator segment 202, individual to the central office level, to restore the switch. All subscribers may have unrestricted connection with a receiving station however, and the receiving subscriber may at his discretion extend such connections either within the exchange or to the 75 central office.

80 Incoming calls from the central office go over the trunk circuit shown in Fig. 3 to a hunting switch 30 which connects them with an idle receiving station F. The receiving subscriber having inquired and found out what is wanted, may then set the companion final selector switch 300 to complete the connection with a desired substation. As soon as the companion final selector switch is set the switch 30 is restored to normal leaving the receiving station 85 ready for the next call.

85 In Fig. 5 are shown the possible connections in a branch exchange employing both first and final selector switches. Either an ordinary substation A or a receiving station 90 E will, upon the initiation of a call, be seized by a line finder 100 and connected to a first selector 500. The subscriber, by operating his calling device then sets the selector 500 in its primary movement on either a level 401 leading to a trunk circuit such as 95 that shown in Fig. 2, a level 400 leading to a trunk circuit such as that shown in Fig. 3, or on the particular level 501 leading to final selectors 200 in whose banks are terminals of the wanted line. If he has chosen a 100 level 501, an idle final selector 200 is automatically selected in the secondary movement of the switch 500. By operating his calling device the subscriber may then directly control the final selector 200 in both 105 its primary and secondary movements to complete a connection with the wanted subscriber's line within the branch exchange. If he has chosen a level 400, the selector 500 110 will in its secondary movement select an idle trunk circuit 406 leading to the central office.

115 If the subscriber A sets the first selector 500 on level 401, an idle trunk circuit 405 will be selected in the secondary movement 120 of the switch 500, whereupon a hunting 125

- switch 25 will pick out an idle receiving subscriber E. The receiving subscriber by operating his calling device may then set another first selector 500 on either of the three 5 levels 501, 400 or 401. If the switch 500 is set on a level 501, the connection will be completed to any wanted substation within the exchange through a final selector switch 200 in the same manner as when the calling 10 subscriber made such a call without the intervention of a receiving subscriber. When the switch 200 has been set the hunting switch 25 releases to leave the receiving subscriber ready for the next call.
- 15 Calls coming in from the central office cause a hunting switch 30 to select the line of an idle receiving subscriber E who answers the call. Having found that an extension of the connection is desired he operates his calling device to set the first selector switch 500 on terminal 501 and then re-operators the calling device to set switch 200 on the terminals of the wanted subscriber's line. The hunting switch 30 releases as soon as 25 the switch 200 is set.
- Having described the general circuit arrangements it is believed that the invention will be readily understood from a detailed description of the setting up of the various 30 possible connections.
- Initiation of a call by a private branch exchange subscriber and the primary setting of the final selector switch.*
- 35 When the subscriber at A lifts his receiver off the hook he operates a line relay 101 over a circuit from grounded battery, right-hand winding of relay 101, back contact and inner armature of relay 114, conductor 115, 40 substation A, outer armature and back contact of relay 114, left-hand winding of relay 101 to ground. Relay 101 in attracting its left-hand armature creates a calling condition upon the multiple 116 of substation A 45 in the finders in which such line appears. In attracting its right-hand armature, relay 101 completes a circuit from ground, its right-hand armature and front contact, conductor 104, back contact and armature of 50 relay 102, through the winding of relay 103 to grounded battery. Relay 103 is energized in this circuit, and locked up from grounded battery through its winding, front contact and left-hand armature over the circuit 55 previously traced. Relay 103, in energizing, places a ground on commutator segment 105 individual to the group of lines of which substation A is a member. A circuit is now completed from grounded battery, right-hand winding of release control relay 120, conductor 121, side switch arms 122 and 123, first position, conductors 124, 109 and 108, back contact and left-hand armature of relay 107, conductor 106 to ground at the 60 right-hand armature and front contact of relay 103. Relay 120 is energized in this circuit and is locked up over a circuit from grounded battery through the right-hand winding, armature and front contact of relay 120 over conductor 108 and the circuit 65 just traced to ground at the right-hand armature of relay 103. A circuit is also completed from ground, front contact and right-hand armature of relay 103, conductor 106, left-hand armature and back contact of relay 107, conductor 108, conductor 109, side switch arms 110 and 111, first position, back contact and armature of magnet 112 through the winding of primary magnet 112 to 70 grounded battery. Primary magnet 112 interrupts its circuit and steps the brushes 117, 118 and 119 around until the group of lines containing station A is reached. When the finder brushes reach the group in which the call originated, a circuit is completed 75 from ground, spring 125, commutator segment 105, brush 113, conductor 126, back contact and right-hand armature of relay 107, side switch arm 127, first position, conductor 128 through the windings of the slow-to-release escape magnet 129 and slow-to-release primary magnet 112 to grounded battery. Magnet 129 is shunted at this time by ground at the armature of primary magnet 112, but when this armature opens near 80 the end of the step, magnet 129 is energized to advance the finder side switch to position 2. The circuit for primary magnet 112 is now broken at side switch arm 111 and the switch stops with a brush set in position to 85 traverse the calling group of lines.
- Magnet 129 is held energized in position 2 of the side switch over a circuit leading from grounded battery, winding magnet 112, winding magnet 129, conductor 128, side switch arm 127, second position, back contact and armature of relay 130 to ground; but magnet 112 is marginal and will not energize in this circuit. A circuit is now completed from grounded battery, winding of 90 secondary magnet 131, armature and back contact of this magnet, conductor 132, inner left-hand armature and front contact of relay 120, side switch arms 123 and 122, second position, conductor 128 in parallel with the circuit for magnet 129 previously traced to ground at the back contact and armature of relay 130.
- Secondary magnet 131 in energizing 95 interrupts its circuit and steps the brushes 117, 118 and 119 to the terminals 116, 133 and 134 of the calling line. When this line is reached a circuit is completed from grounded battery, resistance 135, front contact and left-hand armature of relay 101, conductor 136, terminal 116, brush 117, side switch arms 111 and 110, second position, through the winding of relay 130 to ground. Relay 130 is energized in this circuit and breaks 100 at its armature and back contact the circuit 105
- 110
- 115
- 120

- 130

previously traced for escape magnet 129. This magnet in releasing passes the side switch arms into position 3.

In position 3 of the side switch the cut-off relay 114 is operated over a circuit from grounded battery through the left or both windings of relay 114 (see Figs. 6 and 7), according as the line A is a restricted or a non-restricted line as will appear more fully hereinafter, terminal 116, brush 117, side switch arms 111 and 110, third position, through the winding of relay 196 to ground. Relay 114 in energizing opens the circuit of line relay 101. Relay 101 in retracting its left-hand armature removes the calling condition from the terminals 116 of the line A, and in retracting its right-hand armature it breaks the circuit of relay 103 which thereupon is deenergized. The circuit for relay 102 is broken at the right-hand armature of relay 103, and the line finder starting relays are ready for the next call.

In position 3 of the side switch a circuit is also completed for stepping relay 137 from grounded battery, left-hand winding of said relay, side switch arms 123 and 122 third position, conductors 138 and 139, brush 118, terminal 133 through the apparatus at substation A, terminal 134, brush 119, conductors 140 and 141, side switch arm 142, conductor 143, right-hand winding of relay 137 to ground. Relay 137 in being energized completes a circuit for slow-to-release relay 150, from grounded battery, winding of relay 150, front contact and armature of relay 137, through primary off-normal spring 151 to ground. Relay 150 in attracting its right-hand armature completes a circuit from ground, right-hand armature and front contact of relay 150, conductor 157, back contact and left-hand armature of slow-to-release release magnet 158, conductor 159, contact spring 160 of relay 145, conductor 161 through the righthand winding of relay 162, side switch arm 163, first position, lefthand winding of relay 162 to grounded battery. Circuits are also completed at this time from grounded battery through the right-hand winding of relay 107, and from grounded battery through the left-hand winding of relay 120 in parallel with the circuit just traced, to ground at the righthand armature of relay 150. Relays 162 and 107 are energized in these circuits, and relay 120 is held up after its locking circuit is broken due to the energization of relay 107. Relay 107, in being energized, connects the in-starter wire 164 over conductor 106 to the out-starter wire 165, to permit operation of other line finders in the group to which the finder 100 belongs.

The calling subscriber now receives a distinctive dial tone over a circuit which may be traced from ground through the secondary winding 144 of tone source D. T. outer-

most right-hand armature and back contact of relay 145, side switch arm 146, first position, conductor 147, condensers 148 and 149, side switch arm 122, third position, thence in parallel with the circuit of relay 137 over the talking conductors, through the substation apparatus and back over the talking conductors through the right-hand winding of relay 137 to ground. The subscriber, hearing this tone, now operates his sender S to transmit the first digit of the wanted number. In returning to normal the sender interrupts the circuit of the stepping relay 137 a number of times corresponding to the digit involved. Each time relay 137 retracts its armature, a circuit is completed from ground, primary off-normal spring 151, armature and back contact of relay 137, left-hand armature and front contact of relay 150, side switch arm 152, third position, conductor 153, through the winding of slow-to-release relay 154, conductor 155, side switch arm 156, first position, conductor 204, through the winding of the primary magnet 205 of the final selector switch, conductor 206, middle right-hand armature and back contact of relay 145 to grounded battery. Relay 154 is operated in this circuit, but being slow-to-release remains energized throughout each series of impulses. Relay 150 being slow-to-release also remains energized during the sending of impulses. Primary magnet 205, in response to these impulses, steps the brushes 207, 208 and 209 to the group of terminals in which the line desired by the calling subscriber appears. At the end of this series of impulses, relay 137 holds its armature attracted for a sufficient time to allow relay 154 to be deenergized. When relay 154 was energized it completed a circuit from ground, outer armature and back contact of the final selector release magnet 213, conductor 214, front contact and right-hand armature of relay 154, conductor 166, back contact and armature of relay 167 through the winding of selector escape magnet 168, to grounded battery. Magnet 168 is energized in this circuit, and when this circuit was broken by the deenergization of relay 154, magnet 168 became deenergized to pass the selector side switch arms into position 2.

Establishment of a connection to another private branch exchange station.

If we assume that the subscriber at substation A desired connection to another substation B within the branch exchange, he again operates his calling device to interrupt the circuit of stepping relay 137. At each retraction of the armature of relay 137, a ground impulse is set over the circuit previously traced through relay 154, conductor 155, side switch arm 156, second position, conductor 215, through the winding

of the selector secondary magnet 216, to grounded battery. Secondary magnet 216 is operated by these impulses to step brushes 207, 208 and 209, into engagement with the terminals 210, 211, 212 of the wanted line. Relay 154 and escape magnet 168 are also operated in the impulse circuit and at the conclusion of the impulses, relay 154 in being deenergized breaks the circuit of escape magnet 168 to allow it to become deenergized. Magnet 168 in being deenergized passes the selector side switch into position 3. If the called line is busy, ground potential will be found on its test terminal 212.

15 This ground being applied through brush 209, conductor 169, side switch arm 170, third position, innermost left-hand armature and back contact of relay 171 through the right-hand winding of relay 172, and 20 side switch arm 163, third position, will shunt the right-hand winding of relay 162 which is also connected over conductor 161 and the circuit previously traced to ground at the front contact and right-hand armature of relay 150.

25 Relay 162 will therefore become deenergized and close a circuit from grounded battery through the winding of relay 145, conductor 173, back contact and armature of relay 162, conductor 174, outermost left-hand armature and back contact of relay 171, conductor 175, selector primary off-normal spring 176 to ground. Relay 145 in being energized completes a circuit for release magnet 213 from grounded battery, winding of release magnet 213, conductors 177 and 178, innermost right-hand armature and front contact relay 145, to ground through primary off-normal spring 176. The 30 release magnet 213 is energized in this circuit and locks up over a circuit from grounded battery through its winding, front contact and inner armature and conductor 175 to ground at off-normal spring 176.

35 The energization of the release magnet restores the selector switch to normal.

When relay 145 was energized it completed a locking circuit for itself from grounded battery through its winding, left-hand armature and contact spring 160, conductor 159, left-hand armature and back contact of magnet 158, conductor 157, front contact and right-hand armature of relay 150, to ground. When the selector switch reaches normal, the subscriber at A will receive a busy tone which is transmitted over the following circuit: ground, secondary winding 179 of tone source B. T. outermost right-hand armature and front contact of relay 145, side switch arm 146, first position, conductor 147, condensers 148 and 149 and thence over the circuit previously traced for the dial tone over conductor 143 to ground through the right-hand winding of relay 137. The subscriber hearing this tone

replaces his receiver on its switch-hook, thereby interrupting the circuit of relay 137. Relay 137 in becoming deenergized opens the circuit of relay 150. After a short interval this relay is deenergized and opens at 70 its right-hand armature the circuits for relays 120, 107 and 145. Relay 120 in being deenergized completes a circuit from grounded battery through the winding of finder release magnet 158, outer left-hand armature and back contact of relay 120, conductor 180, back contact and armature of relay 137, spring 151 to ground. The release magnet 158 is energized in this circuit and locks up from grounded battery 75 through its winding, front contact and right-hand armature and spring 151 to ground. The release magnet 158 restores the line finder switch 100 to normal, at 80 which time spring 151 opens to break the locking circuit of magnet 158 and the system is ready for the next call.

If, however, substation B is found idle when the selector side switch passes to position 3, a circuit is completed from grounded battery through the winding of cut-off relay 216, terminal 212, brush 209, conductor 169, side switch arm 170, third position, innermost left-hand armature and back contact of relay 171, through the right-hand winding of relay 172, side switch arm 163, third position, right-hand winding of relay 162, conductor 161, contact spring 160, conductor 159, left-hand armature and back contact of relay 158, conductor 157, front contact and right-hand armature of relay 150 to ground. Relays 172 and 216 are energized in this circuit and relay 162 is maintained energized. Relay 172, in being energized, connects ground over its front contact and right-hand armature, contact and innermost left-hand armature of relay 171 and side switch arm 170, third position, over brush 209 to test terminal 212 to render the called line immediately busy. This ground also shunts the right-hand windings of relays 172 and 162 but they are not deenergized since a substitute circuit is completed immediately from grounded battery through the left-hand winding of relay 162, side switch arm 181, third position, left-hand winding, left-hand armature and front contact of relay 172, conductor 155, side switch arm 156, third position, to ground. The escape magnet 168 is energized over a circuit from grounded battery, through winding of magnet 168, armature and back contact of relay 167, conductor 166, over the circuit just traced to ground at side switch arm 156, third position. Magnet 168 in being energized completes a circuit to apply ringing current to the called line which may be traced from a source of ringing current 11 through the winding of ringing cut-off relay 167, side switch arm 182, third position 130

tion, front contact and inner left-hand armature of magnet 168, conductor 147, side switch arm 183 third position, conductor 184, side switch arm 185, third position, conductor 186, brush 208, terminal 211, through the bell (not shown) substation B, terminal 210, brush 207, conductor 187, side switch arm 188, third position, conductor 189, side switch arm 190, third position, conductor 191, outer left-hand armature and front contact of magnet 168, to ground. Relay 167 is marginal and will not be energized in the circuit just traced until the called subscriber answers. When the called subscriber answers he lowers the resistance of the ringing circuit by shunting the bell with his switch hook, and relay 167 is energized. In being energized, relay 167 opens the circuit previously traced for escape magnet 168, and escape magnet 168 is deenergized to pass the selector side switch into position 4.

Substations A and B are now connected over conductors 140 and 141, side switch arm 142, third position, condenser 193, side switch arm 190 fourth position, conductor 189, side switch arm 188 third position, conductor 187, brush 207, terminal 210, substation B, terminal 211, brush 208, conductor 186, side switch arm 185 third position, conductor 184, side switch arm 183, fourth position, condenser 149, side switch arm 122 third position, conductors 138 and 139, brush 118, terminal 133, conductor 115, through substation A, terminal 134 and brush 119 to conductor 140. Talking current is supplied to the calling line through relay 137, and to the called line from grounded battery, through the left-hand winding of impedance coil 192, side switch arm 183 fourth position and side switch arm 185 third position, ring conductor 186, thence through substation B, tip conductor 187, side switch arm 188 third position and side switch arm 190 fourth position, through the right-hand winding of impedance coil 192, to ground. Relay 162 is held energized throughout the conversation over a circuit from grounded battery, left-hand winding relay 162, side switch arm 163 fourth position, right-hand winding relay 162, conductor 161 and over the circuit previously traced to ground at the right-hand armature of relay 150. Ground is also applied to the sleeve terminal of the called line through side switch arm 170 fourth position, conductor 169, brush 209, and terminal 212 to hold cut-off relay 216 energized, and to furnish a busy test at the multiples of line B in other switches.

At the conclusion of the conversation, the calling subscriber in placing his receiver on its switchhook, opens the circuit of relay 137 which becomes deenergized to open the circuit of relay 150. Relay 150, in being deenergized opens the circuit of relays 120 and 162; finder release magnet 158, and se-

lector release magnet 213 are energized to release the finder and selector switches in the manner described when line B was found to be busy.

Establishment of a connection to a central office trunk.

If the subscriber at station A desires a central office connection, upon hearing the dial tone when the finder side switch reaches position 3, he operates his sender to set selector switch 200 on a level 400 in the final selector bank which leads to central office trunks. The operation of the finder switch and the selector switch in its primary movement is the same as when a particular station B was desired. At the end of the first series of impulses however, auxiliary brush 201 will be in engagement with commutator segment 202 which is individual to the central office level. Upon the deenergization of relay 154 at the conclusion of the first set of impulses, magnet 168 is deenergized to pass the side switch into position 2, and ground is applied through spring 176, conductor 175, left-hand armature and back contact of relay 154, conductor 194, brush 201, commutator segment 202, conductor 195, to the armature of relay 196. If the substation A is restricted to branch exchange calls, its cut-off relay 114 will be connected to terminal 116 through the left-hand winding only, and relay 196 will be energized over a circuit from grounded battery, left-hand winding relay 114, terminal 116, brush 117, side switch arms 111 and 110, third position through the winding of relay 196 to ground. The ground of spring 176, appearing at the armature of relay 196, will therefore be extended over conductor 177 through the winding of release magnet 213 to grounded battery. Magnet 213 will be energized and locked up in the same manner as before and release of the selector switch will take place precisely as though selector 200 had been set on the terminals of a busy substation within the branch exchange. The calling subscriber will receive a busy tone as before and will hang up to release line finder 100 as before.

If, however, substation A is a non-restricted station, its cut-off relay 114, will be connected to terminal 116 through both windings in series, and relay 196 being marginal will not be energized in the circuit previously traced. The ground on the armature of relay 196 will therefore be extended over the back contact of relay 196, side switch arm 197, second position, through the winding of relay 171 to grounded battery. Relay 171 is energized, and locks up over a circuit from grounded battery through its winding, right-hand armature 125 and front contact, conductor 198 and con-

ductor 161 over the circuit previously traced for relay 162 to ground, at the right-hand armature of relay 150. A circuit is therewith completed from grounded battery 8 through the winding of magnet 168, armature and back contact of relay 167, middle left-hand armature and front contact of relay 171, conductor 199, secondary off-normal spring 10, which is closed until the 10 secondary movement of the selector switch begins, spring 176 to ground. Escape magnet 168 is energized in this circuit and held up over a circuit through side switch arm 170, second position, conductor 169, and brush 209 to ground on busy terminals 219 15 of central office trunks after the secondary movement of the selector switch opens contact spring 10. A circuit is also completed from grounded battery through the winding 20 of secondary magnet 216, conductor 215, side switch arm 156, second position, conductor 155, conductor 220, back contact and armature of magnet 216, conductor 221, side switch arm 146, second position, inner armature and front contact of magnet 168, side switch arm 182, second position, innermost left-hand armature and front contact of relay 171, conductor 198 and thence in parallel with the locking circuit of relay 171 to 30 ground at the right-hand armature of relay 150. Stepping magnet 216, makes and breaks this circuit at its armature and back contact, and steps the brushes 207, 208, 209, over the terminals of central office trunks 35 until an idle trunk, indicated by battery potential at test contact 219, is found. At this time, escape magnet 168 is shunted by the battery potential applied through brush 209, side switch arm 170, second position, middle left-hand armature and front contact of relay 171, and back contact and armature of relay 167. Escape magnet 168 is deenergized to pass the selector side switch 40 into position 3, and to open at its inner left-hand armature the circuit of the secondary magnet 216.

In position 3 of the selector side switch, a circuit is completed for finder escape magnet 129 from grounded battery through the winding of magnet 112, winding of magnet 129, conductor 128, side switch arms 127 and 197, third position, right-hand armature and front contact of relay 171, and thence in parallel with the locking circuit of relay 171 over conductors 198 and 161 to ground, at the right-hand armature of relay 150. Escape magnet 129 is energized in this circuit and advances the finder side switch to position 4.

In position 4 of the finder side switch the circuit of stepping relay 137 is interrupted at side switch arms 123 and 142, fourth position, and this relay is deenergized to open the circuit of relay 150. Relay 150, however, is slow-to-release and is not de-

energized at once, but maintains the circuits of relays 171, 120 and 107, and completes a circuit in parallel with said circuits from ground at the right-hand armature of relay 150 over conductor 157 the circuit previously traced to conductor 198, front contact and innermost left-hand armature of relay 171, side switch arm 170, third position conductor 169, brush 209, terminal 219, conductor 222, through the winding of relay 301 to grounded battery. Relay 301 is energized in this circuit and completes a circuit to energize relay 303 which may be traced as follows: ground, right-hand armature and back contact of relay 302, left-hand armature and front contact of relay 301, winding of relay 303 to grounded battery. Relay 303 in being energized completes a circuit from ground, front contact and outer right-hand armature of relay 303, through the winding of relay 304 to grounded battery. Relay 304 is energized and connects the trunk conductors 223 and 224 to the armatures of relay 305. In being energized, relay 303 also completes a circuit from ground, front contact and left-hand armature of relay 303, conductors 306 and 307, outer right-hand armature and back contact of relay 308, through the winding of relay 305 to grounded battery. Relay 305 is energized to complete a circuit from grounded battery through the right-hand winding of relay 309, front contact and inner armature of relay 305, front contact and outer armature of relay 304, ring conductor 223, terminal 218, brush 208, conductor 186, side switch arm 185, fourth position, conductor 139 through the finder brushes and apparatus at substation A, back over tip conductor 140, side switch arm 188, fourth position, conductor 187, brush 207, terminal 217, conductor 224, inner armature and front contact of relay 304, outer armature and front contact of relay 305, through the left-hand winding of relay 309 to ground. Relay 309 is energized in this circuit and closes a circuit from grounded battery through the winding of slow-to-release relay 302, front contact and right-hand armature of relay 309 to ground. Relay 302 in attracting its armatures applies ground through its left-hand armature and front contact to conductor 222 to take the place of the ground formerly applied through the right-hand armature of relay 150 to hold up relays 301, 171, 107 and 120.

When relay 309 was energized it also completed a circuit, from ground, left-hand armature and front contact of relay 309, conductors 310 and 317, through the winding of relay 311, conductor 312, armature and back contact of relay 313 through the winding of relay 314 to grounded battery. Relay 314 is energized in this circuit but relay 311 is marginal and will not be ener-

gized in series with relay 314 which is high wound. Line relay 314 in being energized completes a circuit for call lamp L at the central office operator's position. The operator seeing lamp L lighted inserts the plug 315 of her cord circuit in jack 316 of the line calling. A circuit is thereby completed from grounded battery, left-hand lower winding of repeating coil 318, winding 10 of supervisory relay 319, ring 320, contact spring 321, conductor 312, through the winding of relay 311, conductors 317 and 310, front contact and left-hand armature of relay 309 to ground. The resistance of 15 supervisory relay 319 is relatively low, so that both marginal relay 311 and relay 319 are energized in this circuit. Relay 319 in being energized extinguishes the calling supervisory lamp (not shown). When the 20 operator inserted plug 315 into jack 316, a circuit was also completed from grounded battery (not shown), through the sleeve of plug 315 and jack 316 and the winding of cut-off relay 313 to ground. Cut-off relay 25 313 was energized to extinguish the call lamp L. Relay 311 in being energized completes a circuit from ground, armature and front contact of relay 311 through the winding of relay 308 to grounded battery. Relay 308 is energized and at its outer right-hand armature breaks the circuit of relay 305. At its left-hand armature it closes a 30 low resistance shunt circuit to provide a path for voice current around relay 311 through conductor 322, resistance 323, front contact and left armature, of relay 308, back to the ring conductor 317. Resistance 323, however, is not small enough to cause relay 311 to be deenergized. Relay 305 in being 35 deenergized connects the talking conductors 224 and 223 through to the contact springs of relay 324 and interrupts the circuit of relay 309. Relay 309 in being deenergized breaks the circuit of relay 302, but this relay is slow-to-release and stays 40 up until a substitute circuit is completed as will appear hereinafter.

Relay 308, in attracting its inner right-hand armature completed a circuit from ground, 50 inner right-hand armature of relay 308, through the winding of relay 324 to grounded battery. Relay 324 is locked up over a circuit from grounded battery through its winding, front contact and right-hand armature over conductor 306, left-hand armature and front contact of relay 303 to ground. A circuit is also completed from grounded battery through the winding of slow-to-release relay 325, front contact and outer right-hand 55 armature of relay 308, conductors 307 and 306 to ground at the front contact and left-hand armature of relay 303. Relay 325 in attracting its armature completes the substitute circuit for holding up relay 302 from 60 grounded battery through the winding of 65

relay 302, front contact and armature of relay 325 to ground.

A talking circuit is now completed from substation A over the conductors shown in heavy black to the central office. The central office operator, by depressing a listening key (not shown) may inquire the number desired by the calling subscriber and may thereupon complete the connection to the wanted subscriber in any well known manner.

The release of the connection will occur upon the deenergization of relay 311. At the close of the conversation the calling party in replacing his receiver on its hook 80 breaks the circuit through supervisory relays 311 and 319. Relay 319 in being deenergized lights the calling supervisory lamp (not shown) before the operator who removes plug 315 from jack 316. Relay 311 85 in being deenergized opens the circuit of relay 308 which retracts its armatures. At its outer right-hand armature relay 308 breaks the circuit of relay 325 which retracts its armature to break the circuit of relay 302. Relay 302 in being deenergized, removes ground from conductor 222 thereby opening the circuits of relays 303, 171, 107 and 120 which relays become inert. Relay 303 in retracting its armatures opens the circuits which had held up relays 304 and 324, and the trunk circuit is now in normal condition. Relay 171 in being deenergized completes a circuit for release control relay 145 which may be traced from grounded battery, relay 145, conductor 173, back contact and armature of relay 162, conductor 174, outer-most left-hand armature and back contact of relay 171, conductor 175, through off-normal spring 176 to ground. Relay 145 100 attracts its armatures and completes the previously traced circuit for selector release magnet 213. This magnet causes release of the selector switch in the same way as described for a call between station A and station B. Relay 120 in being deenergized completes the previously traced circuit for finder release magnet 158 which is energized to release the finder switch in the manner previously described and the system is now ready 105 for another call.

Establishment of a connection to a receiving subscriber's station.

If the subscriber at station A desires connection with a receiving subscriber he initiates a call in the same manner as when he desired a central office connection. The line finder 100 operates to connect the calling subscriber's line with an idle selector 200 120 exactly as described when connection with a substation B was desired. The subscriber, upon hearing the dial tone, operates his calling device to send a primary series of impulses to set the selector switch 200 on level 125 130

402 in which the terminals of receiving subscribers appear. At the completion of this series of impulses the finder side switch will be in position 3 and the selector side switch 5 will be in position 2. The selector auxiliary brush 201 will be in engagement with a group segment 226 individual to the receiving subscribers' lines and a circuit will be completed from ground through contact 176, 10 conductor 175, left-hand armature and back contact of relay 154, conductor 194, brush 201, commutator segment 226, conductor 12, arm 197, second position, through the winding of relay 171, to grounded battery. Relay 171 is energized and locks up through 15 its right-hand armature and front contact and conductor 198 to ground at the right-hand armature of relay 150 over the circuit previously traced. A circuit is then completed 20 from ground through off-normal contact 176, secondary off-normal contact 10 closed until the initiation of secondary movement, conductor 199, middle left-hand armature and front contact of relay 171, back 25 contact and left-hand armature of relay 167 through the escape magnet 168 to grounded battery. Magnet 168 is energized in this circuit and after the switch has taken its first secondary step and the off-normal contact 30 10 is opened, is maintained energized in a circuit from battery, winding of magnet 168, armature and back contact of relay 167, front contact and middle left-hand armature of relay 171, arm 170, second position, 35 and brush 209 to ground on busy test terminals 229 of receiving subscribers' trunk lines. A circuit is also completed from grounded battery through the winding of secondary magnet 216, conductor 215, arm 40 156, second position, conductors 155 and 220, back contact and armature of magnet 216, conductor 221, arm 146, second position, inner armature and front contact of magnet 168, arm 182, second position, innermost left- 45 hand armature and front contact of relay 171, and thence in parallel with the locking circuit of said relay to ground at the right-hand armature of relay 150. The secondary magnet 216 makes and breaks this circuit at 50 its left-hand armature and passes the selector brushes over terminals 227, 228 and 229, until an idle set of terminals is reached. The idle condition of these terminals being denoted by absence of ground on sleeve terminal 229, the locking circuit of escape magnet 168 is broken and magnet 168 is de- 55 energized to pass the selector side switch into position 3. In opening its inner armature, magnet 168 permanently opens the circuit of secondary magnet 216 to stop the brushes 207, 208 and 209 in engagement with the idle set of terminals.

In position 3, of the selector side switch a circuit is completed for finder escape mag- 60 net 129 from grounded battery through the winding of magnet 112, magnet 129, conductor 128, arms 127 and 197, third position right-hand armature and front contact of relay 171, and thence in parallel with the locking circuit of relay 171 to ground at the right-hand armature of relay 150. Escape magnet 129 is energized in this circuit to advance the finder side switch to position 4. In position 4 of the finder side switch 70 the circuit of stepping relay 137 is interrupted at side switch arms 123 and 142, fourth position, and this relay 137 is deenergized to open the circuit of relay 150. Relay 150, however, is slow-to-lease and is not deenergized at once, but maintains the 75 circuits of relays 171, 120 and 107 until a substitute ground is provided from the selected trunk circuit. With the finder side switch in position 4, and the selector side switch in position 3, a circuit is completed 80 from grounded battery through the right-hand winding of line relay 230, back contact and innermost left-hand armature of relay 231, terminal 228, brush 208, conductor 186, arm 185, fourth position, conductor 139, brush 118, terminal 133, through the apparatus at station A, terminal 134, brush 119, conductor 140, arm 188, fourth position, conductor 187, brush 207, terminal 227, middle left-hand armature and back contact of relay 231 through the left-hand winding of relay 230 to ground. Relay 230 is energized and completes an energizing circuit for slow-to-release relay 232. Relay 232 in attracting its armature applies 85 ground to terminal 229 to replace ground formerly applied at the right-hand armature of relay 150 for providing a busy test, and holding up relays 171, 107, and 120. A circuit is also completed from ground, armature and front contact of relay 232, conductors 233 and 234, side switch arm 235, first position, right-hand armature and back contact of relay 236, back contact, armature and winding of motor magnet 237 to grounded 90 battery. Magnet 237 makes and breaks this circuit at its left-hand armature and steps brushes 238, 239 and 240 of the hunting switch 25 over terminals 241, 242 and 243 of receiving subscribers' lines. Busy lines 95 are denoted by ground on their test terminals 243 which shunts the right-hand winding of test relay 236 over brush 240. When an idle line is reached, a circuit is completed from grounded battery through both windings of cut-off relay 244, terminal 243, brush 240, right-hand winding of test relay 236, arm 235, first position, conductors 234 and 233 to ground at the front contact and armature of relay 232. Relay 236 in being 100 energized interrupts the circuit of magnet 237 to stop the switch on the selected set of terminals, and at its left-hand armature completes a circuit from grounded battery 105 through the winding of relay 245, left-hand 110

120

125

130

winding, front contact and armature of relay 236, thence over the circuit previously traced to ground at the armature of relay 232. This circuit energizes relay 245 and 5 holds up relay 236 after its right-hand winding has been shunted by the attraction of its right-hand armature to provide a busy ground at terminal 243. Relay 245 in attracting its right-hand armatures 10 completes a circuit to ring the call bell if the receiving subscriber is equipped with the type of apparatus shown at E or to energize its relay 326 if the station has the equipment shown at F, which circuit may 15 be traced from a source of ringing current through the right-hand winding of relay 246, back contact and inner right-hand armature of said relay, front contact and inner right-hand armature of relay 245, brush 239, terminal 242 through the call bell or 20 relay, according to the equipment at the receiving station, terminal 241, brush 238, outer right-hand armature and front contact of relay 245, outer right-hand armature 25 and back contact of relay 246 to ground. Relay 246 is marginal and will not be energized in this circuit until the resistance is lowered when the called subscriber answers 30 in the case of station E, or throws his answering key 327 in the case of station F. At this time relay 246 attracts its armatures to interrupt the calling current and completes at its left-hand armature a holding circuit for itself which may be traced from 35 grounded battery, left-hand winding of relay 246, left-hand armature and front contact of said relay, front contact and left-hand armature of relay 245 to ground. In attracting its right-hand armatures, relay 40 246, also completes a connection between the calling substation and the receiving substation, talking current being supplied through both windings of relay 230. Supervisory relay 247 is energized in the talking 45 circuit.

Transfer of a call from a receiving subscriber's station to a regular private branch exchange station.

50 The calling subscriber may now obtain any information he desires from the receiving subscriber. In case it is desired to extend the connection to a substation within the branch exchange such as that shown at 55 C, the receiving subscriber operates his calling device to interrupt the circuit through supervisory relay 247. When relay 247 was first energized it completed a circuit from grounded battery through the winding of 60 slow-to-release relay 248, conductor 249, front contact and armature of relay 247 to ground. When relay 247 becomes deenergized in response to the first impulse caused 65 by the operation of the receiving subscriber's sender, a circuit is completed from ground,

armature and back contact of relay 247, normal contact 250 of relay 251, inner right-hand armature and front contact of relay 248, through the winding of slow-to-release relay 252, side switch arms 253 and 254, first 70 position, front contact and inner armature of relay 255, through the winding of primary magnet 256 to grounded battery. Relay 255 was energized when relay 232 first attracted its armature, over a circuit 75 from grounded battery, right-hand winding of relay 255, arm 259, first position, left-hand winding of relay 255, conductor 257, back contact and armature of release magnet 258, conductor 233 to ground at the front contact and armature of relay 232. Magnet 256 steps the brushes 260, 261 and 262 of companion final switch 20, over the terminals in its bank. In case the called substation 80 is not in the first group of terminals, the receiving subscriber in operating his calling device will send more than one primary impulse. In response to the first impulse, slow-to-release relay 252 is energized 85 and remains operated throughout each series 90 of impulses. Relay 252 completes at its left-hand armature an energizing circuit for relay 251 from ground, left-hand armature and front contact of relay 252, through relay 251 to grounded battery. A circuit is 95 also completed from grounded battery through the winding of companion final escape magnet 263, armature and back contact of relay 264, conductor 265 to ground at the front contact and left-hand armature of relay 252. When relay 251 was energized 100 it completed a circuit for relay 266 from grounded battery, right-hand winding of relay 266, front contact and inner left-hand armature of relay 251, thence over the talking 105 conductors through the apparatus at substation E, and back through the outer left-hand armature and front contact of relay 251 and left-hand winding of relay 266 110 to ground. Relay 266 in attracting its armature provides a substitute circuit to hold up relay 248 after relay 247 has retracted its armature during the first impulse. In response to succeeding interruptions caused by 115 the operation of the sender at substation E, relay 266 vibrates its armature. Each time that the armature of relay 266 is retracted, a circuit is completed from ground, armature and back contact of relay 266, right-hand armature of relay 251, and contact lever of normal contact 250, inner right-hand armature and front contact of relay 248, thence over the path previously traced 120 through the winding of the primary magnet 256 to grounded battery. Magnet 256 in response to these impulses steps the companion final brushes 260, 261 and 262 to the desired group of terminals. At the completion of the first series of impulses, relay 125 266 remains energized long enough to allow 130

relay 252 to become deenergized. Relay 252 in being deenergized opens the circuits previously traced for relay 251 and for the escape magnet 263. Magnet 263 in being deenergized steps the companion final side switch into position 2. Relay 251 in being deenergized again completes the circuit from relay 230 through the substation E which operates relay 247.

10 The receiving subscriber now sends a series of impulses to set the switch 20 on the terminals of the desired line. In response to the first of these impulses, relay 247 is deenergized to complete a circuit from 15 grounded battery through the winding of the secondary magnet 267, arms 254, and 253, second position, through the winding of relay 252, front contact and inner right-hand armature of relay 248, normal contact 20 250 of relay 251 to ground at the back contact and armature of relay 247. Relay 252 is energized in this circuit and operates relay 251 and the escape magnet 263 in the same manner as during the primary 25 impulses. The secondary magnet 267 steps the brushes 260, 261 and 262 of switch 20 one step in their secondary movement. In case more than one impulse is sent, relay 266 is again included in the circuit with 30 the sender at substation E and vibrates its armature to complete the circuit for secondary magnet 267 from ground, armature and back contact of relay 266, right-hand armature of relay 251 and contact lever of normal contact of relay 251, inner right-hand armature and front contact of relay 248 and thence over the path traced for the first impulse through the winding of secondary magnet 267 to grounded battery. Magnet 267 in response to these 35 impulses steps the brushes of the switch 20 to the terminals of the desired line. At the conclusion of this series of impulses, relay 266 remains energized to break the circuit of relay 252, and after a short interval this relay retracts its armatures to open the circuits of relay 251 and escape magnet 263. Magnet 263 in being deenergized, passes the side switch into position 40 3. Relay 251, in retracting its left-hand armatures again completes the circuit between station A and station E to energize relay 247. Relay 248 being slow to release remains energized as long as the receiving 45 subscriber holds his connection, since it is energized over a circuit from grounded battery through its winding to ground at either the armature and front contact of relay 247, or of relay 266 since one of these relays is energized at all times until station 50 E is disconnected from the line. Relay 248 at its left-hand armature provides a substitute circuit for holding up relay 232 in case the calling subscriber should, by abandoning the call, open the circuit of line

relay 230. Release is therefore under the control of the receiving subscriber while he is extending the connection.

When brushes 260, 261 and 262 are set on terminals 268, 269 and 270, at the conclusion of the secondary impulses the called line is tested. If this line is busy, ground will be present on its terminal 270 as will hereinafter appear. Side switch arm 259 in passing from position 2 to 3, interrupts the previously traced circuit which held relay 255 energized in positions 1 and 2, of the side switch and transfers the control of this relay to test relay 271. If the tested line is busy, ground on its test terminal 70 will be connected through brush 262 and arm 272, third position, to the left-hand winding of relay 271 to shunt this relay which is also connected to ground through the outer left-hand armature and back contact of relay 273, arm 259, third position, left-hand winding of relay 255, conductor 257, back contact and armature of magnet 258 and conductor 233 to the front contact 75 and ground at armature of relay 232. As no circuit is now completed for relay 255, it retracts its armatures to complete a circuit for magnet 258 which may be traced from grounded battery through the winding of magnet 258, outer armature and back contact of relay 255 through primary off-normal spring 274 to ground. Release magnet 258 is energized in this circuit and restores the companion final brushes and side switch arms to normal, at which time off-normal spring 274 opens to break the circuit through magnet 258. In attracting its armature, magnet 258 completes a circuit from grounded battery through the winding of relay 275, front contact and armature of magnet 258 and conductor 233, to ground 80 at the front contact and armature of relay 232. Relay 275 is energized in this circuit and locks up over a circuit from grounded battery through its winding front contact and right-hand armature and conductor 276 to ground, at the front contact and armature of relay 247. In attracting its left-hand armature, relay 275 completes a circuit from ground, through the secondary winding of busy tone source 287, front contact and left-hand armature of relay 275, inner left-hand armature and back contact of relay 277 through the condenser 278 and tip conductor 279 through the receiving subscriber's substation E, thence back over the ring conductor through the innermost armature and back contact of relay 231 to the right-hand winding of relay 230 and grounded battery. 85

The receiving subscriber hearing this busy tone informs the calling subscriber that the called line is busy and may then, by operating his sender, reset the companion final switch 20 in accordance with the de- 90 95 100 105 110 115 120 125 130

sire of the calling subscriber, or he may release the entire connection by replacing his receiver on its hook. The operation of resetting the companion final switch is the same as when this switch was first set and need not, therefore, be described. If the subscriber does not desire any further connection, the receiving subscriber in replacing his receiver on its hook interrupts the circuit for relay 247, and relay 266 being inert at this time, relay 248 is deenergized to break at its left-hand armature the substitute circuit for relay 232. When the calling subscriber hangs up his receiver he breaks at his switch-hook the circuit for relay 230. In becoming deenergized, relay 230 interrupts at its armature the circuit for relay 232 which thereupon is deenergized. Relay 232 in becoming deenergized removes the holding ground from terminal 229 thereby interrupting the circuits of relays 171 and 120. Relays 171 and 120 are deenergized to cause the restoration of the selector and finder switches in the manner previously described when a central office call was made from station A. Relay 232 in being deenergized also completes a circuit from ground, armature and back contact of relay 232, outermost left-hand armature and back contact of relay 231, through spring 280 closed when hunting switch 25 is off-normal, through the winding of magnet 281 to grounded battery. Magnet 281 is energized to restore hunting switch 25 to normal position at which time spring 280 opens to render magnet 281 inert. The system is now ready for the next call.

If the line C, when tested, is found to be idle, no ground will appear on its sleeve terminal 270, and a circuit will be completed from grounded battery through the winding of cut-off relay 282, terminal 270, brush 262, arm 272, third position, through the left-hand winding of relay 271, back contact and outer left-hand armature of relay 273, arm 259, third position, through the left-hand winding of relay 255, back contact and armature of magnet 258 over conductor 233 to ground at the front contact and armature of relay 232. Cut-off relay 282 and test relay 271 are energized in this circuit, and release control relay 255 is maintained energized. Relay 271 in attracting its left-hand armature connects a dead ground to terminal 270 to provide a busy test and to shunt the left-hand winding of relay 271. Relay 271 is not deenergized however, since a substitute circuit is completed from grounded battery to the right-hand winding of relay 255, arm 283, third position, right-hand winding, front contact and armature of relay 271, conductor 257 to ground at the armature of relay 232 over the circuit previously traced. Relays

255 and 271 are held energized in this circuit. Escape magnet 263 is now energized from grounded battery, winding of magnet 263, armature and back contact of relay 264, conductor 265 through the right-hand winding of relay 271, and thence over the circuit just traced to ground at the armature of relay 232. Magnet 263 in attracting its armatures closes a circuit to ring the call bell at substation C which may be traced from a source of ring current through the winding of ringing trip relay 264, inner armature and front contact of magnet 263, arm 284, third position, brush 261 terminal 269, through the apparatus at station C, terminal 268, brush 260, arm 285, third position, outer armature and front contact of magnet 263 and arm 286, third position, to ground. Relay 264 is marginal and will not be energized in this circuit until the subscriber at C lowers the resistance of the ringing circuit by removing his receiver from its hook. Relay 264 thereupon is energized and breaks at its armature the circuit of escape magnet 263. Escape magnet 263 in becoming deenergized passes the companion final side switch into fourth position. Stations A and C are now connected through companion final brushes 260, and 261, arms 285 and 284, fourth position, selector terminals 227 and 228, selector brushes 207 and 208, arms 188 and 185, fourth position, and the conductors shown in heavy black. In fourth position, release control relay 255 is held energized over a circuit from grounded battery through the right-hand winding of relay 255, arm 259, fourth position, left-hand winding of relay 255, conductor 257, back contact and armature of magnet 258, and conductor 233, to ground at the armature of relay 232. Ground is connected through the right-hand armature and back contact of relay 277, arm 272, fourth position, and brush 262 to terminal 270, to provide busy potential and to hold cut-off relay 282 energized. Talking current is supplied through both windings of relay 230. Side switch arm 235 in passing to fourth position interrupts the holding circuit for relays 245 and 236. Relay 245 when deenergized interrupts at its left-hand armature the circuit for relay 246, and at its right-hand armatures the circuit for relay 247. Relay 247 in being deenergized breaks the circuit of relay 248. In retracting its armatures, relay 248 completes a circuit from ground, armature and front contact of relay 232, conductors 233 and 234, arm 235, fourth position, outer right-hand armature and back contact of relay 248, off-normal spring 280, through the winding of release magnet 281, to grounded battery. Magnet 281 releases the hunting switch 25 in the same manner as when substation C was found 130

to be busy and the receiving station E is ready for the next call.

When the subscribers at A and C complete their conversation, and hang up their receivers, they interrupt at their switch-hooks the circuit of relay 230. Relay 230 in being deenergized opens the circuit of relay 232 which retracts its armature. (Ground being removed from conductor 233 and terminal 10 229, release control relay 255 retracts its armature to complete a circuit for magnet 258. Relays 171 and 120 also retract their armatures, and release of switches 100, 200 and 20 takes place in the manner described when 15 substation C was found to be busy.

Establishment of a connection from a restricted service station to a central office trunk.

20 If the subscriber at station A is restricted to calls within the private branch exchange, he is unable to get a central office connection without the intervention of a receiving subscriber. Should he therefore desire a central 25 office connection, he initiates a call in the usual manner and sets the selector switch 200 with which his line is associated on terminals leading to a hunting switch 25. The operation of the line finder and selector 30 switch is the same as described when a receiving subscriber was called for the purpose of getting information. The hunting switch 25 picks an idle receiving subscriber in the manner previously described and sub- 35 station A is then connected to a receiving station such as E. The calling subscriber informs the receiving subscriber of his desire for a central office connection, and the receiving subscriber may, at his discretion, 40 extend the call to the central office. To do this, the receiving subscriber operates his sender to set the companion final brushes 260, 261, and 262 in their primary movement on a level 400 in which appear terminals of central office trunks. The operation 45 of the final switch in its primary movement is accomplished in the manner previously described when a call was being extended to a substation C within the exchange, except 50 that at the end of the primary movement auxiliary brush 288 will rest on commutator segment 289 individual to the central office level. When relay 252 is deenergized at the end of the primary impulses, a circuit 55 is completed from grounded battery through the winding of relay 273, conductors 290, 291 and 292, commutator segment 289, brush 288, conductor 293, back contact and right-hand armature of relay 252, conductor 257, 60 back contact and armature of magnet 258, and conductor 233 to ground at the right-hand armature of relay 232. Relay 273 is energized and completes a locking circuit for itself which may be traced from grounded 65 battery through the winding, inner left- hand armature and front contact of relay 273, conductor 257, and thence over the circuit just traced to ground at the right-hand armature of relay 232. Release control relay 255 is held up in first and second positions from grounded battery, right-hand winding of relay 255, arm 259, first position, left-hand winding of relay 255, conductor 257 to ground at the armature of relay 232. 70

When relay 252 became deenergized it also 75 interrupted at its left-hand armature and inner front contact, the circuit for escape magnet 263. Magnet 263 in being deenergized passes the side switch into second position. In second position of the side switch, escape magnet 263 is again energized over a circuit from grounded battery through the winding of magnet 263, armature and back contact of relay 264, conductor 265, front contact and outer right-hand armature of relay 273, conductor 294, arm 272, second position, and brush 262 to ground on terminals 219 of busy central office trunks. Magnet 263 in attracting its outer armature completes a circuit from grounded battery 80 through the winding of secondary magnet 267, arms 254 and 253, second position, armature and back contact of magnet 267, inner right-hand armature and front contact of relay 273, outer armature and front contact of magnet 263, arm 286, second position, conductors 257 and 233 to ground at the armature of relay 232. Secondary magnet 267 makes and breaks this circuit at its armature and back contact, and steps the brushes 260, 90 261 and 262 over the terminals of central office trunks. When an idle set of terminals is found, absence of ground potential on test terminal 219 opens the circuit which has been holding up magnet 263, to allow this 95 magnet to be deenergized. Magnet 263 in being deenergized passes the side switch into third position and at its outer armature breaks the circuit of secondary magnet 267 to stop the brushes 260, 261 and 262 in en- 100 gagement with terminals 217, 218 and 219 of the selected trunk line. 105

Relay 277 was energized in parallel with relay 273 and had a holding circuit provided from grounded battery through the 110 winding of relay 277, conductors 291 and 290, inner left-hand armature and front contact of relay 273 and thence in parallel with the locking circuit of relay 273 to ground at the armature of relay 232. When the side 115 switch reaches third position, ground is therefore applied to terminal 219, through the armature of relay 232, conductor 233, back contact and right-hand armature of relay 231, contact springs 296 of relay 277, 120 arm 272, third position, and brush 262 to energize relay 301 and to provide busy potential. In third position the escape magnet 263 is energized from grounded battery 125 through the winding of magnet 263, arma- 130

ture and back contact of relay 264, conductors 265 and 297, arms 253 and 254, third position, front contact and outer left-hand armature of relay 277 to ground. A circuit 5 is thereupon completed from a source of ringing current, through the winding of relay 264, front contact and inner armature of magnet 263, arm 298, third position, back contact and left-hand armature of relay 275, 10 inner left-hand armature and front contact of relay 277, resistance 299, conductor 22, outer armature and front contact of magnet 263, arm 286, third position to ground. Resistance 299 is low enough to allow relay 264 15 to be energized in this circuit thereby interrupting the circuit previously traced for the escape magnet 263 which is deenergized to pass the side switch into fourth position.

With the side switch in fourth position a 20 circuit is completed to energize relay 231 which may be traced from grounded battery, winding of relay 231, side switch arms 254, and 253, fourth position, conductor 290, inner left-hand armature and front contact 25 of relay 273, and thence in parallel with the locking circuit of relay 273, to ground at the armature of relay 232. Relay 231 in attracting its left-hand armatures breaks 30 the circuit of relay 230 which in being deenergized opens the circuit of relay 232. Relay 232 is slow-to-release and does not therefore retract its armature until ground has been applied to conductor 233, from relay 302 in the selected trunk circuit. Relay 35 301 which it will be remembered was energized immediately upon the seizure of the trunk when the companion final side switch was in third position, is held energized after the side switch passes to fourth position over a circuit from grounded battery 40 through the winding of relay 301, conductor 222, terminal 219, brush 262, arm 272, fourth position, right-hand armature and contact springs 296 of relay 277, right-hand armature and front contact of relay 231, and thence in parallel with the circuit just traced 45 for relay 231 to ground at the armature of relay 232.

The energization of relay 301, causes the 50 same operation of the relays in the trunk circuit as was described when the selector switch 200 was set direct on terminals of such a trunk circuit, and need not be described in detail here. When line relay 309 55 attracts its armatures to energize relay 302, relay 302 at its left-hand armature applies ground to conductor 222 and thence through terminal 219, brush 262, arm 272, fourth position, right-hand armature and contact 60 springs 296 of relay 277, right-hand armature and front contact of relay 231, arms 254 and 253, fourth position, conductor 290, inner left-hand armature and front contact of relay 273, conductor 257, back contact and armature of magnet 258, conductor 233 to

terminal 229. Relays 255, 273, 277 and 231 of the companion final switch are held energized in this circuit throughout the remainder of the connection. Relays 120, 107 and 171 are also held up over this circuit. 70 When the companion final side switch passed into fourth position, the receiving subscriber at station E was disconnected and the switch 25 was restored in the same manner as was described when a call was completed between station A and station C. 75

The central office operator's call lamp L, Fig. 3, is lighted in the same manner as was described when a direct central office call, 80 without the intervention of a receiving subscriber, was made and the operator inserts her plug 315 in jack 316, thereby energizing relays 311 and 308 in the manner previously described, and depresses her listening key (not shown). A talking circuit is now completed between the operator's head set (not shown), and substation A, energy being supplied over a circuit from grounded battery, lower left-hand winding of repeating coil 318, supervisory relay 319, ring 320, spring 321, conductors 312 and 322, resistance 323, front contact and left-hand armature of relay 308, inner left-hand armature and front contact of relay 324, back contact and inner left-hand armature of relay 305, front contact and outer right-hand armature of relay 304, conductor 223, terminal 218, brush 261, arm 284, fourth position, terminal 228, brush 208, conductor 186, arm 185 fourth position, conductor 139, brush 118, terminal 133, through the apparatus at substation A, terminal 134, brush 119, conductor 140, arm 188, fourth position, conductor 187, brush 207, terminal 227, arm 285, fourth position, brush 260, terminal 217, conductor 224, inner armature and front contact of relay 304, outer armature and back contact of relay 305, front contact and outer left-hand armature of relay 324, conductor 328, spring 329, tip of plug 315, upper left-hand winding of repeating coil 318 to ground. 100 105 110 115 120 125 130

The operator inquires the number desired by the calling party and completes the connection in the usual manner. At the conclusion of the conversation when the calling subscriber replaces his receiver on its hook, 115 he interrupts the circuit just traced which has been holding supervisory relays 311 and 319 energized. Relay 319 in being deenergized lights its associated supervisory lamp (not shown) and the operator removes plug 315 from its jack. Relay 311 in being deenergized opens the circuit of relay 308. Relay 308 in retracting its armatures closes the circuit of relay 305 from grounded battery through the winding of relay 305, back contact and outer right-hand armature of relay 308, conductors 307 and 306, left-hand armature and front contact of relay 303 to ground. In case the calling sub- 130

scriber at station A desires another central office connection immediately, he does not leave his receiver on its hook, but immediately removes it, thereby completing a circuit 5 from grounded battery through the right-hand winding of relay 309, front contact and inner armature of relay 305, front contact and outer armature of relay 304, conductor 223, terminal 218, brush 261 and 10 thence over the circuit previously traced through the apparatus at substation A, and back through brush 260, terminal 217, conductor 224, inner armature and front contact of relay 304, outer armature and front 15 contact of relay 305 through the left-hand winding of relay 309 to ground. Relay 309 at its right-hand armature completes a circuit to hold up slow-to-release relay 302 when slow-to-release relay 325 is deenergized 20 due to the retraction of the outer right-hand armature of relay 308. In attracting its left-hand armature, relay 309 operates central office line, relay 314 to light the call lamp L in the manner previously 25 described. The operator again inserts her plug 315 in jack 316 thereby operating relay 311 over the circuit previously traced. Relay 311 in attracting its armature completes a circuit for relay 308 which attracts 30 its armatures to cut-off relay 305. Relay 305 in being deenergized completes the previously traced talking circuit between substation A and the central office.

In case the subscriber at station A did not 35 desire any central office connection, he would leave his receiver on its switchhook, so that no circuit would be completed for relay 309, and shortly after the deenergization of relay 308, relay 325 would retract its armature to open the circuit of relay 302. Relay 302 in being deenergized removes 40 from conductor 222 the ground which has been holding up relays 255, 273, 277, 231, 171, 107 and 120. Relays 255, 171 and 120 45 in being deenergized cause the release, respectively, of the companion final switch 20, the selector switch 200 and the line finder switch 100, in the manner described for the 50 release of connection between substations A and C, and the system is now in normal condition ready for other calls.

Establishment of a call from the central office to the private branch exchange.

55 On calls from the central office to the private branch exchange, the operator inserts her plug 315 in a jack 316 of an idle trunk circuit leading to the private branch exchange. A circuit is thereupon completed 60 from grounded battery through the lower left-hand winding of repeating coil 318, supervisory relay 319, ring 320, spring 321, conductor 312, winding of relay 311, conductor 317, left-hand armature and back 65 contact of relay 308, through the winding of relay 330, conductors 353 and 328, spring 329, tip of plug 315 through the upper left-hand winding of repeating coil 318 to ground. Relay 330 is of relatively high resistance and is energized in this circuit but 70 does not allow sufficient current to flow to energize relays 311 or 319. Relay 330 in attracting its armature completes a circuit for relay 302. A circuit is thereupon completed from grounded battery through the 75 winding of relay 301, conductor 222, front contact and left-hand armature of relay 302 to ground. Relay 301 in attracting its right-hand armature closes a circuit from ground, right-hand armature and front contact of relay 301, conductor 331, armature and back contact of magnet 332, side switch arm 333, first position, through the left-hand winding of relay 334, arm 335, first position, conductor 336 through the right-hand winding of relay 334 to grounded battery. Relay 334 is energized in this circuit and locks up from grounded battery through its right-hand winding, conductor 336, arm 335, first position, left-hand winding front 80 contact and armature of relay 334, back contact and armature of magnet 332, and conductor 331 to ground at the right-hand armature of relay 301. Relay 302 in applying ground to conductor 222 also renders 85 multiple terminals 219 of this trunk line busy.

After the operator inserts her plug 315 in the jack of the trunk line, ringing current is impressed on the called line from a 90 source of ringing current (not shown), through ring 320, spring 321, conductor 312, winding of relay 311, inner left-hand armature and back contact of relay 324, condenser 337, back contact and outer left-hand 95 armature of relay 324, conductor 328, spring 329, tip of plug 315, upper left-hand winding of repeating coil 318 to ground. As the resistance of this path is low, relay 311 is energized to operate relay 308. Relay 100 308 in attracting its armatures completes a circuit from ground, front contact and inner right-hand armature of relay 308, through the winding of relay 324 to grounded battery. A circuit is thereupon 105 completed from grounded battery through the winding of relay 325, front contact and outer right-hand armature of relay 308, right-hand armature and front contact of relay 324, inner right-hand armature and 110 front contact of relay 308 to ground. Relay 325 in attracting its armature energizes relay 338 and provides a substitute circuit over its closed front contacts to hold relay 302 energized, after the retraction of the armature of relay 330 has interrupted its original circuit. The circuit of relay 330 was interrupted at the left-hand armature of relay 308 when this relay was energized. The 115 relay 302 being slow-to-release remained up 120

125 65 contact of relay 308, through the winding of relay 330, conductors 353 and 328, spring 329, tip of plug 315 through the upper left-hand winding of repeating coil 318 to ground. Relay 330 is of relatively high resistance and is energized in this circuit but 70 does not allow sufficient current to flow to energize relays 311 or 319. Relay 330 in attracting its armature completes a circuit for relay 302. A circuit is thereupon completed from grounded battery through the 75 winding of relay 301, conductor 222, front contact and left-hand armature of relay 302 to ground. Relay 301 in attracting its right-hand armature closes a circuit from ground, right-hand armature and front contact of relay 301, conductor 331, armature and back contact of magnet 332, side switch arm 333, first position, through the left-hand winding of relay 334, arm 335, first position, conductor 336 through the right-hand winding of relay 334 to grounded battery. Relay 334 is energized in this circuit and locks up from grounded battery through its right-hand winding, conductor 336, arm 335, first position, left-hand winding front 80 contact and armature of relay 334, back contact and armature of magnet 332, and conductor 331 to ground at the right-hand armature of relay 301. Relay 302 in applying ground to conductor 222 also renders 85 multiple terminals 219 of this trunk line busy.

until its substitute circuit was completed. Relay 338 in being energized completes a locking circuit for itself from grounded battery through its winding, left-hand armature and front contact to ground at the right-hand armature of relay 302. Relay 324 is locked up over a circuit from grounded battery through its winding, front contact and right-hand armature and conductor 306 to ground at the right-hand armature and front contact of relay 338. In attracting its left-hand armatures, relay 324 interrupted the ringing current circuit to cause relay 311 to be deenergized, thereby 5 breaking the circuit of relay 308, which in retracting its armatures completes the previously traced circuit for relay 330, and opens the circuit of relay 325. Relay 302 is held up by ground at the armature of relay 330 and relay 338 is held up over its locking circuit after relay 325 retracts its armature. In retracting its outer right hand armature relay 308 completed an energizing circuit for relay 305 which may be traced 10 from grounded battery through the winding of relay 305, back contact and outer right-hand armature of relay 308, conductors 307 and 306, and the right-hand armature and front contact of relay 338, to ground.

20 In attracting its right-hand armature, relay 338 completed a circuit from ground, front contact and right-hand armature of relay 338, left-hand armature and back contact of relay 303, conductor 339, arm 340, first position, right-hand armature and back contact of relay 341, back contact and armature of magnet 342 through the winding of said magnet to grounded battery. Magnet 342 makes and breaks this circuit at its 25 armature and back contact and steps the brushes of the hunting switch 30 over the terminals leading to receiving subscribers' stations. Busy terminals are denoted by ground on sleeve terminal 343 which shunts the right-hand winding of relay 341. When an idle terminal is reached, a circuit is completed from grounded battery through both windings of cut-off relay 344, terminal 343, brush 345, right-hand winding of relay 341, arm 340, first position, conductor 339, back contact and left-hand armature of relay 303 to ground at the right-hand armature and front contact of relay 338. Relay 341 attracts its armatures, at its right-hand 30 armature opening the circuit of magnet 342 to stop the switch 30 on an idle set of terminals, and applying ground from the front contact and right-hand armature of relay 338 to test terminal 343 to provide a busy 35 test. At its left-hand armature, relay 341 completes a circuit from grounded battery through the winding of relay 346, left-hand winding, front contact and armature of relay 341, and thence in parallel with the circuit of relay 344 to ground at the right-hand 40 armature of relay 338. Relay 346 is energized in this circuit and relay 341 is held up after its right hand winding has been shunted. Relay 346 in attracting its right-hand armatures, completes a circuit from a source of ringing current through the right-hand winding of relay 347, back contact and inner right-hand armature of said relay, front contact and inner right-hand armature of relay 346, brush 348, terminal 349 through the left-hand winding of relay 326, condenser 350, terminal 351, brush 352, outer right-hand armature and front contact of relay 346, outer right-hand armature and back contact of relay 347 to ground. 45

Relay 347 is marginal and will not be energized in this circuit at this time. Relay 326 however attracts its armature completing a circuit from grounded battery through lamp 354, right-hand winding, front contact and armature of relay 326, normal contact of answering key 327, to ground. Lamp 354 lights and informs the receiving subscriber that a call is awaiting attention on his associated line. The receiving subscriber thereupon throws his answering key 327, breaking the circuit for lamp 354 which goes out. In operating the answering key a low resistance shunt circuit is completed in parallel with the circuit through the left-hand winding of relay 326 and relay 347 is now energized. In attracting its left-hand armature, relay 347 completes a locking circuit for itself, while in attracting its right-hand armatures relay 347 interrupts the ringing circuit and closes a circuit for relay 309, which may be traced from grounded battery through the right-hand winding of relay 309, front contact and inner armature of relay 305, conductor 356, relay 357, spring 359 of relay 358, front contact and inner right-hand armature of relay 347, front contact and inner right-hand armature of relay 346, brush 348, terminal 349, lowest spring of key 327, through the apparatus at substation F, top spring of key 327, terminal 351, brush 352, outer right-hand armature and front contact of relay 346, outer right-hand armature and front contact of relay 347, inner left-hand armature and back contact of relay 358, outer armature and front contact of relay 305, through the left-hand winding of relay 309 to ground. Relay 309 is energized and in attracting its left-hand armature completes a circuit from grounded battery, through the lower left-hand winding of repeating coil 318, winding of relay 319, ring 320, spring 321 conductor 312, winding of relay 311, conductors 317 and 310, front contact and left-hand armature of relay 309 to ground. Relays 319 and 311 are energized in this circuit, relay 319 operating its associated supervisory lamp (not shown) to inform the central office operator that the call has been answered, and relay 50

55

60

65

- 311 operating relay 308 as before. Relay 308, in attracting its armatures, breaks the circuit of relay 305 which thereupon is de-energized. In retracting its armatures, relay 305 completes a talking connection from the central office to the substation F, battery being supplied from grounded battery through the lower left-hand winding of repeating coil 318, winding of relay 319, ring 320, spring 321, conductor 312, winding of relay 311, conductor 317, inner left-hand armature and front contact of relay 324, back contact and inner armature of relay 305, conductor 356 winding of relay 357, spring 359 of relay 358, front contact and inner right-hand armature of relay 347, front contact and inner right-hand armature of relay 346, brush 348, terminal 349, lowest spring of key 327, substation F, up- per spring of key 327, terminal 351, brush 352, outer right-hand armature and front contact of relay 346, outer right-hand armature and front contact of relay 347, inner left-hand armature and back contact of relay 358, outer armature and back contact of relay 305, front contact and outer left-hand armature of relay 324, conductor 328, spring 329, tip of plug 315, upper left-hand winding of repeating coil 319 to ground. A path for voice current is closed in parallel with relay 311 through conductor 322, resistance 323, front contact and left-hand armature of relay 308 and conductor 310.
- The calling party may now obtain any desired information from the receiving subscriber at station F who may extend the call to any other station within the private branch exchange in accordance with the desires of the calling party. If connection is desired with station D, the receiving subscriber at F operates his calling device to set the companion final switch 300 on the terminals of the desired line. When relay 357 was first energized a circuit was completed for slow-to-release relay 360 from grounded battery through the winding of relay 360, front contact and armature of relay 357, to ground. The first impulse sent from station F interrupts the circuit previously traced for relay 357 and this relay in retracting its armature establishes a circuit from ground, armature and back contact of relay 357, spring 361 of relay 358, armature and front contact of relay 360, through the winding of slow-to-release relay 362, side switch arm 363, first position, through the winding of primary magnet 364, to grounded battery. Relay 362 is energized in this circuit and being slow-to-release, remains energized throughout each series of impulses. Primary magnet 364 is energized and moves the brushes of switch 300 one step in their primary direction. Relay 362 completed a circuit from ground, front contact and armature of relay 362, through the winding of relay 358, to grounded battery, to energize relay 358, and also completed a circuit from ground, springs of relay 362, arm 366, first position, back contact and armature of relay 367, through the winding of the escape magnet 368 to grounded battery.
- In case the line of the called subscriber does not terminate in the first group of contacts in the bank of switch 300, more than one impulse will be sent from station F, the second and succeeding impulses will interrupt the circuit for relay 369 which was completed when relay 358 was energized. The circuit of relay 369 extends from grounded battery, left-hand winding of relay 369, springs 370 of relay 358, thence over the circuit traced through the apparatus at station F, and back through the inner left-hand armature and front contact of relay 358 and the right-hand winding of relay 369 to ground. Each time that this relay retracts its armature in response to an impulse, a circuit is completed from ground, armature and back contact of relay 369, right-hand armature and front contact of relay 358, armature and front contact of relay 360, through the winding of relay 362, arm 363, first position, through the winding of magnet 364 to grounded battery. Relay 362 is maintained energized and magnet 364 steps the brush of switch 300 to the group in which the terminals of the called line appear. Relay 360 is maintained energized throughout each series of impulses by a circuit through the armature and front contact of relay 369.
- At the conclusion of the primary set of impulses, relay 369 holds its armature attracted long enough to allow relay 362 to be deenergized. In retracting its armature this relay opens the circuits previously traced for relay 358 and escape magnet 368. The escape magnet 368 in being deenergized advances the companion final side switch arms to their second position. Relay 358 in being deenergized opens the circuit of relay 369 and completes the original circuit from the central office through station F. Relay 357 is again energized in this circuit. During the time that relay 358 was energized, supervisory relay 319 and relay 311 were held energized over a circuit which may be traced from the ground and one of the left-hand windings of the repeating coil at the central office and the talking conductors as far as spring 359, outer left-hand armature and front contact of relay 358 and resistance 371, to the other left-hand winding.
- The first impulse of the secondary series interrupts the circuit through relay 357 and completes a circuit from ground, armature and back contact of relay 357, spring 361 of relay 358, armature and front contact of relay 360, through the winding of relay 362, arm 363, second position, through the wind-

ing of secondary magnet 372, to grounded battery. Relay 362 is energized and completes the circuits for relay 358, as before and for magnet 368, over arm 366, second 5 position. Magnet 372 steps the brushes of switch 300 one step in their secondary movement. Relay 358 closes the previously traced circuit for relay 369 and the circuit for holding up the central office connection. If 10 more than one impulse is sent, relay 369 vibrates its armature in response to the second and other impulses. Each time relay 369 retracts its armature it completes a circuit from ground, armature and back contact of relay 369, right-hand armature and front contact of relay 358 and thence over the circuit previously traced, through the winding of secondary magnet 372 to grounded battery. Magnet 372 steps the brushes of 15 switch 300 to the terminals of the called line. At the conclusion of these impulses, relay 362 is deenergized, breaking the circuit of escape magnet 368 which in being deenergized passes the side switch arms to 20 their third position.

In third position of the side switch, the circuit of release control relay 334 is dependent upon the condition of the called line. If this line is busy, ground potential will be 25 present on terminal 373 and will be connected over the lowest brush of switch 300, arm 374, third position, left-hand winding of relay 375, arm 335, third position, to the left-hand winding of relay 334. As this 30 winding of relay 334 is also connected over a circuit previously traced, to ground at the right-hand armature of relay 301, relay 334 is deenergized. Release magnet 382 is then 35 energized from grounded battery, winding of magnet 382, right-hand armature and back contact of relay 334, spring 376, closed when switch 300 is off-normal, to ground. Magnet 382 restores the brushes and the 40 side switch arms of companion final switch 300 to normal and completes at its armature a circuit from grounded battery through the winding of relay 377, front contact and armature of relay 332, conductor 331, front contact and right-hand armature of relay 45 301 to ground. Relay 377 is energized and locks up over a circuit from grounded battery through its winding, front contact and right-hand armature, and front contact and armature of relay 357 to ground. At its left-hand 50 armature, relay 377 completes a circuit from ground through the secondary winding of busy tone source 378, front contact and left-hand armature of relay 377, condenser 379, and thence over the circuit previously traced 55 through the apparatus at sub-station F and back to grounded battery at the central office. The receiving subscriber hearing this 60 busy tone, informs the calling party that the desired line is busy and may thereupon 65 extend the call to another sub-station or

may release the entire connection. The operation of extending the call to any other sub-station in the private branch exchange is the same as was described for extending it to station D and need not be entered into 70 further.

In case no further connection is desired the subscriber at station F returns his answering key 327 to its normal position, thereby interrupting the circuit, previously 75 traced, which has been holding relays 319 and 311 energized. Relay 319 in being deenergized operates its associated supervisory lamp (not shown) and the central office operator removes plug 315 from jack 316. 80 Relay 311 in retracting its armature opens the circuit of relay 308 which thereupon breaks the circuit of relay 325. Relay 325 in being deenergized interrupts the circuits of relays 302 and 338. Relay 338 in retracting its right-hand armature breaks the locking circuit of relay 324 and this relay becomes inert. Relay 302 in retracting its left-hand armature, removes the busy potential from conductor 222 and relay 301 is deenergized. A circuit is also completed from 85 ground through the left-hand armature and back contact of relay 302, conductor 380, spring 381 closed when switch 30 is in off-normal position, through the winding of release magnet 382 to grounded battery. Magnet 382 is energized in this circuit and restores switch 30 to normal position at which time the circuit for magnet 382 is interrupted at spring 381. As relay 338 in retracting its right-hand armature removed 90 the ground from conductor 339, there is no longer any circuit through relay 341 and this relay is deenergized. Relays 346 and 347 in turn become inert and the system is in 95 normal condition ready for the next call.

If the called line D is idle, when the side switch moves into its third position a circuit is completed from grounded battery through the winding of cut-off relay 383, terminal 373, lowermost brush of switch 300, arm 374 third position, left-hand winding of relay 375, arm 335, third position, left-hand winding, front contact and armature of relay 334, back contact and armature of magnet 382, conductor 331, front contact and right-hand armature of relay 301 to ground. Relays 383 and 375 are energized in this circuit and relay 334 is maintained energized. Relay 375 in attracting its left-hand armature supplies ground to terminal 373 to furnish a busy test and hold up relay 383. This ground also shunts the left-hand winding of relay 375, but this relay is not deenergized 100 since a substitute circuit is completed from grounded battery through the right-hand winding of relay 334, conductor 336, right-hand winding of relay 375, front contact and right-hand armature of said relay, arm 333, third position, back contact and armature 105 110 115 120 125 130

of magnet 332, conductor 331 to ground at the right-hand armature of relay 301. A circuit is now completed from grounded battery through the winding of escape magnet 368, armature and back contact of relay 367, arm 366, third position, through the right-hand winding of relay 375 and thence in parallel with the circuit just traced, to ground at the right-hand armature of relay 301. Magnet 368 in being energized applies ringing current to the called line over a circuit which may be traced from a source of ringing current through the winding of slow-to-release relay 367, front contact and inner armature of magnet 368, arm 384, third position, middle brush of switch 300, middle terminal of sub-station D, through the ringer at sub-station D, uppermost terminal of this sub-station, brush of switch 300, arm 385, third position, outer armature and front contact of magnet 368 to ground. The call bell at station D is rung in this circuit, but relay 367 is marginal and is not energized until the resistance of this circuit is lowered when the subscriber at D answers. At this time relay 367, in attracting its armature, breaks the circuit of magnet 368, which is deenergized. In becoming deenergized magnet 368 passes the side switch arms into fourth position. In this position a talking circuit is completed from station D to the central office and thence to the called party, battery being supplied from the central office, from grounded battery through left-hand lower winding of repeating coil 318, winding of relay 319, ring 320, spring 321, conductor 312, winding of relay 311, conductor 317, inner left-hand armature and front contact of relay 324, back contact and inner left-hand armature of relay 305, front contact and outer armature of relay 304, arm 384, fourth position, middle brush and terminal of switch 300, apparatus at station D, upper terminal and brush of switch 300, arm 385, fourth position, inner armature and front contact of relay 304, outer armature and back contact of relay 305, front contact and outer left-hand armature of relay 324, conductor 328, spring 329, tip of plug 315, upper left-hand winding of repeating coil 318 to ground. Relay 304 was energized over a circuit from grounded battery, winding of relay 304, arm 333, fourth position, back contact and armature of magnet 332, conductor 331, front contact and armature of relay 301 to ground. Cut-off relay 383 is held up and busy potential is supplied from ground, through arm 374, fourth position, lower brush of switch 300, terminal 373, through the winding of relay 383 to grounded battery. Relay 334 is held energized over a circuit from grounded battery, right-hand winding of relay 384, conductor 386, arm 335, fourth position, left-hand winding, front contact and armature of relay 334 and thence over the circuit previously traced, to ground at the right-hand armature of relay 301. When the side switch reaches fourth position an energizing circuit for magnet 382 is completed from grounded battery through the winding of said magnet, off-normal spring 381, arm 340, fourth position, conductor 389, back contact and left-hand armature of relay 303, right-hand armature and front contact of relay 338 to ground. Magnet 382 restores switch 30 to normal and the multiples of terminals 343, 349 and 351 are again selectable.

At the conclusion of the conversation when the subscriber at station D replaces his receiver he interrupts at the switchhook the previously traced circuit for relays 319 and 311. In response to the deenergization of relay 311 the other relays associated with this trunk circuit become inert in the same manner as was described when line D was found to be busy. Relay 301 in retracting its armature breaks the circuit for relay 334 which is deenergized to complete the previously traced circuit for release magnet 332. Magnet 332 restores the brushes and side switch arms of the companion final switch 300 to normal and the system is then ready for the next call.

It will be seen that a receiving subscriber equipped with a cordless board such as is shown at F, may answer calls coming to him over more than one line by simply operating the answering key associated with the line originating the call. If at any time he desires to hold one call while answering another, he presses the holding key 355. This interposes a resistance of substantially equal amount to that of the substation, thereby holding energized such relays as were in this condition before the holding key was depressed. By then releasing answering key 327 associated with the line on which the call is being held and depressing the answering key of the line on which he wishes to answer the call, he may establish connection with the second calling line and may then extend the call on either line or release the call on either line, and so on, for as many lines as the board is equipped to accommodate. With the exception of the ability to handle more than one call at a time the apparatus at F performs no functions which the apparatus at E would not perform fully as well. If an ordinary substation be substituted for the board F, the ringing circuit instead of extending through the left-hand winding of relay 326 extends through the call bell at the sub-station. Relay 347 is energized when the receiver is removed from its hook instead of at the time answering key 327 is depressed. In either case the operation of the receiving subscriber's impulse transmitter causes relay 357 or 369 to

vibrate its armature, thereby setting the switch 300 on any desired line. In releasing the connection an operator equipped with an ordinary sub-set, breaks the talking circuit 5 in replacing his receiver on its switchhook as effectively as an operator with a board such as F breaks the circuit in releasing the answering key 327.

The multiples of the terminals 351, 349 10 and 343 of the lines leading to station F as well as multiples of terminals 241, 242 and 243 of the line E also appear in the terminal banks of the line finder switches 100 as shown at 31, of final selector switches as 15 shown at 32, and of companion final switches such as 20. Thus it is possible for a receiving subscriber to initiate a call in exactly the same manner as for any other subscriber and it is possible for any subscriber 20 in the private branch exchange to make connection with a particular receiving subscriber by setting his final selector switch 200 on the terminals of the desired receiving subscriber's line.

25 What is claimed is:

1. In a telephone system, a calling subscriber's line provided with a substation sender, a selective switch accessible to said line, a trunk circuit terminating in said selective switch, a non-numerical switch associated with said trunk line, subscribers' lines each provided with a substation sender terminating in said non-numerical switch, means responsive to the selective actuation 30 of said substation sender for setting said selective switch on said trunk line, means responsive to the extension of said calling subscriber's line through said selective switch to said trunk line to actuate said non-numerical 35 switch to further automatically extend said calling subscriber's line to one of said lines terminating in said non-numerical switch, a companion selective switch associated with said trunk line, subscribers' lines terminating 40 in said companion selective switch, and means under control of the substation sender of the subscriber's line to which the said calling subscriber's line has been extended by said non-numerical switch to set said companion 45 selective switch to extend said calling subscriber's line to one of said subscribers' lines terminating in said companion selective switch.

2. In a telephone system, calling lines and 55 called lines, a selective switch, means for connecting one of said calling lines with the active contacts of said selective switch, a trunk circuit having a plurality of terminals including the passive contacts of said 60 selective switch, the active contacts of a non-numerical switch and the active contacts of a companion selective switch, said non-numerical switch and said companion selective switch, receiving lines terminating 65 in the passive contacts of said non-numerical

switch and in substation sets, said called lines terminating in the passive contacts of said companion selective switch, means comprising a substation sender at said calling line for selectively operating said selective switch to connect said calling line with said trunk circuit, means responsive to such connection for operating said non-numerical switch to connect said trunk circuit with an idle one of said receiving lines. 70 and means comprising a substation sender at a receiving substation for selectively operating said companion selective switch to complete a connection over said trunk circuit between said calling and said called 80 line.

3. In a telephone system, a calling line, a selective switch having a primary and a secondary movement, means for connecting said calling line with the active contacts of said selective switch, subscribers' lines and trunk circuits terminating in the passive contacts of said selective switch, means actuated at said calling line for controlling said selective switch in its primary and secondary movements to establish a connection between said calling line and any one of said subscribers' lines, means responsive to a particular operation of said selective switch in its primary movement to initiate its secondary movement and to stop said switch in engagement with the terminals of an idle one of said trunk circuits, a non-numerical switch and a companion selective 90 switch in which said trunk circuit terminates, receiving lines terminating in said non-numerical switch and called lines terminating in said companion selective switch, means responsive to the connection of said calling line with said trunk circuit to operate said non-numerical switch to establish a connection between said trunk circuit and an idle one of said receiving lines, and means controlled at said receiving line to actuate said companion selective switch 95 to complete a connection between said calling line and any one of said called lines. 100

4. In a telephone system, a calling line, a selective switch having a primary and a secondary movement, means for connecting said calling line with the active contacts of said selective switch, subscribers' lines and trunk circuits terminating in the passive contacts of said selective switch, means actuated at said calling line for controlling said selective switch in its primary and secondary movements to establish a connection between said calling line and any one of said subscribers' lines, means responsive to a particular operation of said selective switch in its primary movement to initiate its secondary movement and to stop said switch in engagement with the terminals of an idle one of said trunk circuits, a non-numerical 110 switch and a companion selective switch 115 to complete a connection between said calling line and any one of said called lines. 120

which said trunk circuit terminates, receiving lines terminating in said non-numerical switch and called lines terminating in said companion selective switch, means responsive to the connection of said calling line with said trunk circuit to operate said non-numerical switch to establish a connection between said trunk circuit and an idle one of said receiving lines, means controlled at said receiving line to actuate said companion selective switch to complete a connection between said calling line and any one of said called lines, and means responsive to the completion of said connection for releasing said non-numerical switch to disconnect said receiving line from said trunk circuit.

5. In a telephone system, a calling line, a selective switch having a primary and a secondary movement, means for connecting said calling line with the active contacts of said selective switch, subscribers' lines, central office trunk circuits and local trunk circuits terminating in the passive contacts of said selective switch, means controlled at said calling line for operating said selective switch to establish a connection between said calling line and any one of said subscribers' lines, means responsive to a particular operation of said selective switch in its primary movement to initiate its secondary movement and to stop said switch in engagement with the terminals of an idle one of said central office trunk circuits, said means being responsive to another operation of said selective switch in its primary movement to cause said switch to connect said calling line with an idle one of said local trunk circuits, a non-numerical switch in which said local trunk circuit terminates, receiving lines terminating in said non-numerical switch and in substation sets, means actuated in response to the connection of said calling line with said idle local trunk circuit to operate said non-numerical switch to establish connection between said local trunk circuit and an idle one of said receiving lines, a companion selective switch in whose active contacts said local trunk circuit terminates and whose passive contacts are multiples of the passive contacts of said first mentioned selective switch, an impulse transmitting device at said receiving substation for controlling the operation of said companion selective switch to complete a connection between said calling line and any one of said central office trunk circuits, and means responsive to the completion of said connection for releasing said non-numerical switch to disconnect said receiving line from said local trunk circuit.

40 6. In a telephone system, a calling line, a non-numerical switch in which said local trunk circuit terminates, receiving lines terminating in said non-numerical switch and in substation sets, means actuated in response to the connection of said calling line with said idle local trunk circuit to operate said non-numerical switch to establish connection between said local trunk circuit and an idle one of said receiving lines, a companion selective switch in whose active contacts said local trunk circuit terminates and whose passive contacts are multiples of the passive contacts of said first mentioned selective switch, and an impulse transmitting device at said receiving substation for controlling the operation of said companion selective switch to complete a connection between said calling line and any one of said subscribers' lines or an idle one of said central office trunk circuits or said local trunk circuits.

45 7. In a telephone system, a calling line, a selective switch having a primary and a secondary movement, means for connecting said calling line with the active contacts of said selective switch, subscribers' lines, central office trunk circuits and local trunk cir-

cuits terminating in the passive contacts of said selective switch, means controlled at said calling line for operating said selective switch to establish a connection between said calling line and any one of said subscribers' lines, means responsive to a particular operation of said selective switch in its primary movement to initiate its secondary movement and to stop said switch in engagement with the terminals of an idle one of said central office trunk circuits, said means being responsive to another operation of said selective switch in its primary movement to cause said switch to connect said calling line with an idle one of said local trunk circuits, a non-numerical switch in which said local trunk circuit terminates, receiving lines terminating in said non-numerical switch and in substation sets, means actuated in response to the connection of said calling line with said idle local trunk circuit to operate said non-numerical switch to establish connection between said local trunk circuit and an idle one of said receiving lines, a companion selective switch in whose active contacts said local trunk circuit terminates and whose passive contacts are multiples of the passive contacts of said first mentioned selective switch, an impulse transmitting device at said receiving substation for controlling the operation of said companion selective switch to complete a connection between said calling line and any one of said central office trunk circuits, and means responsive to the completion of said connection for releasing said non-numerical switch to disconnect said receiving line from said local trunk circuit.

50 8. In a telephone system, an operator's position, multiple jacks at said position, a non-numerical switch, a selective switch, a companion selective switch, a trunk circuit connecting said multiple jacks with the active contacts of said non-numerical and companion selective switches and the passive contacts of said first mentioned selective switch, receiving lines terminating in the passive contacts of said non-numerical switch and in substation sets, subscribers' lines terminating in the passive contacts of said companion selective switch and in substations, means for extending a connection from said operator's position to said trunk circuit, means responsive to such extension for operating said non-numerical switch to connect an idle one of said receiving lines to said trunk circuit and for rendering non-selectable the terminals of said trunk circuit in said first mentioned selective switch, and an impulse transmitting device at said selected receiving substation for controlling the operation of said companion selective switch to complete a connection over said trunk circuit between said operator's position and any one of said subscribers' lines.

55 9. In a telephone system, an operator's

position, multiple jacks at said position, a non-numerical switch, a selective switch, a companion selective switch, a trunk circuit connecting said multiple jacks with the 5 active contacts of said non-numerical and companion selective switches and the passive contacts of said first mentioned selective switch, receiving lines terminating in the passive contacts of said non-numerical switch 10 and in substation sets, subscribers' lines terminating in the passive contacts of said companion selective switch and in substations, means for extending a connection from said operator's position to said trunk circuit, 15 means responsive to such extension for operating said non-numerical switch to connect an idle one of said receiving lines to said trunk circuit and for rendering non-selectable the terminals of said trunk circuit in 20 said first mentioned selective switch, an impulse transmitting device at said selected receiving substation for controlling the operation of said companion selective switch to complete a connection over said trunk circuit 25 between said operator's position and any one of said subscribers' lines, and means responsive to the completion of said connection for releasing said non-numerical switch to disconnect said receiving line from said 30 trunk circuit.

9. In a telephone system, a calling line, a plurality of selective switches, means for connecting said calling line with an idle one of said selective switches, trunk circuits

terminating in said selective switches, means 35 controlled at said calling line for operating said idle selective switch to seize an idle trunk circuit, a non-numerical switch whose active contacts are terminals of said trunk circuit receiving lines terminating in the 40 passive contacts of said non-numerical switch, a motor magnet to operate said non-numerical switch, a quick relay, a ringing relay, and a slow release relay associated with said non-numerical switch, said quick 45 relay operated upon the seizure of said trunk circuit to operate said slow release relay, said slow release relay rendering said trunk circuit non-selectable and operating said motor magnet to step said non-numerical switch 50 into engagement with the terminals of an idle receiving line, a test relay energized when said terminals are engaged to stop said switch and to complete a circuit for said ringing relay, a ringing cut-off relay to 55 apply ringing current to said receiving line upon the actuation of said ringing relay, and a circuit for said ringing cut-off relay completed when the call on said receiving line is answered, said ringing cut-off relay 60 in energizing cutting-off ringing current and completing a circuit for voice current between said calling line and said receiving line.

In witness whereof, I hereunto subscribe 65 my name this 20th day of November, A. D. 1919.

SAMUEL B. WILLIAMS, JR.
